UNITED STATES PATENT OFFICE.

SHERMAN WILLIAM LADD, OF BOSTON, AND EDWARD ALLIN STIGGINS, OF BEVERLY, MASSACHUSETTS, ASSIGNEES TO UNITED SHOE MACHINERY COMPANY, OF PATERSON, NEW JERSEY, AND BOSTON, MASSACHUSETTS, A CORPORATION OF NEW JERSEY.

GRIPPER FOR LASTING-MACHINES.

1,005,234.

Specification of Letters Patent. Patented Oct. 10, 1911.

Original application filed March 20, 1901, Serial No. 52,040. Divided and this application filed October 13, 1902. Serial No. 127,083.

To all whom it may concern:

Be it known that we, SHERMAN W. LADD and EDWARD A. STIGGINS, citizens of the United States, and residents, respectively, of 5 Boston, in the county of Suffolk and State of Massachusetts, and of Beverly, in the county of Essex and State of Massachusetts, have invented an Improvement in Grippers for Lasting-Machines, of which the following description, in connection with the accompanying drawing, is a specification, like reference characters on the drawings indicating like parts in the several figures.

This invention relates to grippers and particularly to grippers for pulling uppers over lasts in the lasting operation and other similar operations, and is a division of an application for United States Letters Patent, Serial No. 52,040 filed by us March 20th, 20 1901 for improvements in lasting machines.

The grippers in which our invention is herein shown as embodied constitute one of the operating mechanisms of a lasting machine which may be of the type shown in the 25 United States Letters Patent granted to Sherman W. Ladd and Ronald F. McFeeley, No. 584,744, June 15th, 1897. Reference may be had to this patent for a full description of a lasting machine provided with grippers 30 of this class and with operating mechanism therefor and also for a full disclosure of the relation of the grippers to the other mechanisms of a lasting machine. As fully explained in said patent, a shoe is prepared for 35 lasting by assembling the upper, lining and inner-sole upon the last with the upper and lining drawn over upon the inner-sole at the toe, and at the sides, and sometimes at the heel also, and secured by a tack or tacks in 40 each of these places to hold the parts in relative position. The parts thus fitted to a last form what is known as a "pulled-over" shoe.

The edge portion of the upper of a pulled-over shoe extends in an irregular line more 45 or less distant from the edge of the inner-sole, being drawn over parallel with the inner-sole where the tacks are inserted, while it stands up at an angle to the inner-sole between the tacks. This relation of the edge 50 of the upper to the inner-sole varies considerably in different pulled-over shoes, but the shoe shown in Figure 4 of the accompanying drawings may be regarded as typical. An-

other condition which is frequently met is that the upper is small for the last and the 55 edge of the upper at certain places projects very little from the edge of the last.

It is the object of the present invention to improve the construction and operation of grippers of this class, to enable them to operate successfully under the various conditions found in different shoes, some of which are above referred to.

To this end an important feature of the invention consists in giving the movable 65 gripper member a peculiar movement while the grippers are closing, by which the said movable member is caused to travel in a curved path, moving first away from the fixed member and then toward said fixed 70 member, to cause the movable member to gather in and draw the edge portion of the upper toward the fixed member.

Another feature of our invention consists in pivotally mounting the movable gripper 75 member and rocking said member upon its pivot during the closing movement to change the angular relation of said member to the fixed member and thereby increase further the range of action of the grippers in gathering in portions of the upper lying distant 80 from the fixed gripper member, and also the short portions which project but little above the edge of the last. As herein shown the path of movement of the movable gripper member is determined by means which act 85 on that member at a plurality of points in its length in such manner as to control its movements toward and from the coöperating gripper member.

It is characteristic of the illustrated construction that the gripping is effected in two steps in the first of which the movable jaw is moved lengthwise to embrace the stock and caused to approach approximately to the 95 other and in the second of which the movable jaw is rocked sharply toward the fixed jaw to effect final closing and locking upon the stock. This final closing may be effected by means additional to that which effects the 100 approximate closing and may include a surface inclined to the direction of movement for crowding the movable jaw toward its companion jaw.

In order that our invention may be clearly 105 understood the same will be described with

reference to the accompanying drawings and to the reference characters marked thereon and forming a part of this specification and the several features of the invention above 5 enumerated, together with other features and characteristics of the invention which will appear herein, including certain details of construction and combination of parts, will be pointed out in the claims at the end of 10 the description.

Fig. 1 is a side elevation of the grippers with the jaws in position to be closed upon the projecting edge portion of the upper of a shoe. Fig. 2 is a longitudinal sectional view 15 of the grippers with the jaws closed, the line of section being indicated by $x-x$, Fig. 3. Fig. 3 is a right hand side elevation of the grippers as shown in Fig. 2. Fig. 4 is a perspective view of a shoe prepared for lasting.

20 The gripper jaws or members 14 and 16 are supported respectively on the sleeve 13 and the rod 15, which sleeve and rod constitute the shanks of the grippers by relative right line movements of which the 25 grippers are opened and closed, and by which they are moved together to stretch the upper, as described in said Letters Patent. The rod is contained within the sleeve and is arranged for longitudinal movement relative thereto in actuating the gripper jaws 30 from the open position shown in Fig. 1 to the closed position shown in Fig. 2.

The gripper jaw 14 is rigidly connected to its shank 13, and this gripper jaw will herein be referred to as the fixed gripper member or fixed jaw. The other jaw 16 is flexibly connected to its shank 15 and is moved with relation to the fixed jaw in closing the grippers to engage the upper. The jaw 16 will 40 herein be referred to as the movable gripper member or movable jaw. The shank 15 which is a push rod is forked at its lower end, as shown in Fig. 3, and the movable jaw 16 is likewise forked. The link 17 is 45 hinged to the forked ends of the shank 15 and jaw 16. The two jaws, 14 and 16, are connected by a link 18 which, as herein shown, extends from the movable jaw 16 to a pivot located in the lower frame-like portion of the sleeve 13. The point of connection of the link with the jaw 16 is so located 50 that in the longitudinal movement of jaw 16 with relation to jaw 14 from the open position to the closed position said link 18 will cause the jaw 16 to travel in a curved path, moving first outwardly and away from the jaw 14 and then inwardly toward said jaw. The effect of so connecting the jaws is to extend or enlarge the opening between them 55 during the movement from the extreme open position shown in Fig. 1 to the closed position shown in Fig. 2.

In order to extend further or to enlarge the opening between the jaws and to cause 60 the lower end of the movable jaw to move in

a path which extends farther from the fixed jaw, so that it may pass around and gather in a portion of the upper, when said upper is remote from the fixed jaw, or a portion which extends but little above the edge of the last, said movable jaw is caused to rock upon its pivotal connection with the link 18, thereby to retard the inward movement of the lower end of the jaw, which would otherwise be caused by said link, until the last part of the descent of the jaw is reached and then to rock it sharply inwardly toward the fixed jaw for gripping the upper. This movement is obtained in the embodiment of the invention herein shown by providing a cam surface 20, shown as supported on the shank 13 in rigid relation to the fixed jaw, and by forming the upper end of the movable jaw with a surface 21 adapted to engage said cam surface. These surfaces 20 and 21 are so shaped that in conjunction with the link 18 they cause the lower end of the movable jaw 16 when passing from the position shown in Fig. 1 to that shown in Fig. 2 to rock gradually outwardly until the latter part of the closing movement is reached during which the lower end of the movable jaw is rocked first gradually inwardly to gather in the upper and then caused to rock sharply toward the fixed jaw for gripping the upper. In order to hold said surfaces 20 and 21 in engagement, and cause the movable jaw 16 to stand away from the other jaw when the grippers are open and to cause said movable jaw to be rocked outwardly during the first portion of the descent, said jaw 16 is provided with a socket 24 in which is located a spring-pressed plunger 25, and the link 17 is provided with a shoulder adapted to be engaged by said spring plunger to flex the joint between said movable jaw and link and hold the cam surface 21 on the movable jaw against the cam surface 20 on the fixed jaw.

This invention is not limited, except as 11 stated in the claims, to the construction of the grippers mechanism by which the described movements are obtained.

In Fig. 1, the dotted line $y-y$ indicates the curved path of movement of the lower end of the movable jaw obtained by means of the specific construction of the parts herein shown. From this drawing it is clear that the said lower end of the movable jaw is arranged so that it will pass over and around an edge portion, as z , of an upper, when the said edge portion is too remote from the fixed jaw to have been engaged by a movement of said jaw in a straight line. The range of action of the grippers therefore is materially increased by causing the movable jaw to travel in a curved path and is increased further by rocking said movable jaw during the closing movement. Under this arrangement the movable gripper may 125

be said to "reach out" for the upper, and we find in practice that the difficulties above referred to, caused by the widely varying conditions in which pulled-over shoes are presented to the lasting machine, are to a great extent obviated by the present invention. The point about which the jaw 16 moves is defined in some of the claims to be fixed, from which it will be understood that in the combination covered by these claims the point, for example, that pivot connecting the link 18 to the shank 13, remains stationary in the initial closing movement during which the jaw is rocked about said pivot.

15 While we have described our improved grippers as applicable to the particular type of machine mentioned, our invention is not limited to grippers designed for use in a specific form of machine, but is broad enough 20 to include grippers having the characteristics recited in whatever relation said grippers may be employed.

Having described and illustrated our invention in the best form now known to us, 25 what we desire to secure by United States Letters Patent is:—

1. In a machine for working an upper over a last, a grippers mechanism comprising a pair of jaws and means whereby one 30 of said jaws may be moved relatively to the other to close the grippers, in combination with means for causing said movable jaw, in its movement to close the grippers, to reach out and gather in the upper.

35 2. A grippers mechanism comprising a pair of jaws mounted on suitable shanks, said shanks being relatively movable to open and close the jaws, means connecting said jaws to cause one of them in approaching 40 and receding from the other to move in a curved path, and means for varying the angular relation of said jaws to each other during the closing and opening movements.

45 3. A grippers mechanism comprising one jaw rigidly connected to its shank and a second jaw movable toward the first jaw to grip the work, a shank for said second jaw mounted for movement in a right line, a flexible connection between said shank and 50 said second jaw, and a link connection between said two jaws constructed and arranged to cause the movable jaw to travel in a curved path in moving toward the fixed jaw.

55 4. A grippers mechanism comprising one jaw rigidly mounted on its shank, a second jaw flexibly mounted on its shank, said shanks being movable longitudinally to close the jaws, and means to rock said second jaw during its movement toward the first jaw, to cause its lower end to travel around the edge of the work.

60 5. A grippers mechanism comprising a pair of jaws mounted on suitable shanks which are relatively movable longitudinally

to open and close the jaws, a flexible connection between one of said jaws and its shank, a connection between the jaws whereon the movable jaw rocks toward the fixed jaw, and means arranged to engage the 70 movable jaw and rock it with relation to the fixed jaw during the longitudinal movement of said shanks and jaws.

6. A grippers mechanism comprising a pair of jaws mounted on suitable shanks 75 and relatively movable to grip the work, a flexible connection between one of said jaws and its shank, a movable fulcrum upon which said last-named jaw is mounted, and means to rock said jaw about said fulcrum 80 during the last portion of its closing movement.

7. A grippers mechanism for use in working an upper over a last and comprising a relatively fixed jaw and a jaw movable toward the shoe in closing against the fixed 85 jaw and means to cause said movable jaw to move toward the fixed jaw in a curved path, in combination with means to rock said movable jaw toward the fixed jaw during 90 the latter part of such movement.

8. A pair of grippers comprising a shank, a jaw, a hinge joint connecting said jaw and shank, a second jaw suitably attached to its shank, and a yielding element acting on the 95 members of said hinge joint to tend to hold the jaws normally separated.

9. Grippers for lasting machines, comprising a pair of jaws one of which is movable with relation to the other, means to cause 100 said movable jaw to move toward the relatively fixed jaw in a curved path, and yielding means tending to hold said jaws normally extended for gathering in the upper of the shoe being lasted, in combination with 105 means to rock said movable jaw against the tension of said yielding means for gripping the upper.

10. Grippers for lasting machines, comprising one jaw rigidly connected to its 110 shank, a second jaw movable toward the first and flexibly connected to its shank, a link connecting said two jaws and constructed and arranged to cause the movable jaw to follow a curved path in moving toward the 115 other jaw, and means to rock said movable jaw toward the other jaw during a portion of said movement.

11. Grippers for lasting machines, comprising one jaw rigidly connected to its 120 shank and a second jaw movable toward the first and flexibly connected to its shank, a link attached to the rigid jaw and pivoted between the ends of said movable jaw to cause the movable jaw to follow a curved path 125 when moved toward the rigid jaw, and co-operating engaging surfaces on said jaws to rock said movable jaw toward the rigid jaw during a portion of its movement.

12. Grippers for lasting machines, com- 130

- prising one jaw rigidly connected to its shank and a second jaw movable toward the first and connected to its shank by a link, means connecting said jaws together, a 5 shoulder on said link, and a spring-pressed plunger mounted in said second jaw in position to engage said shoulder on the link to tend to hold said movable jaw away from the fixed jaw, in combination with means operative during the latter portion of the movement of said movable jaw to rock it toward the fixed jaw to grip the work.
13. A grippers mechanism, comprising a pair of gripper jaws mounted for relative movement longitudinally toward and from gripping position, and means for actuating one of said jaws laterally away from the other jaw during a portion of said relative longitudinal movement toward gripping position and laterally toward the other jaw for gripping the stock during a latter portion of said relative longitudinal movement.
14. A grippers mechanism for use in working an upper over a last and comprising a pair of jaws mounted for movement of one of the jaws longitudinally toward the shoe in approaching the gripping position, and means for actuating one of said jaws gradually toward the other jaw during the latter part of said relative longitudinal movement toward gripping position and then sharply toward the other jaw for gripping the stock.
15. In a grippers mechanism, the combination with a movable gripper member and a coöperating fixed gripper member, of means for actuating said movable gripper member toward the fixed gripper member, and other means acting upon said movable member at a plurality of points for determining the path of its movement.
16. A grippers mechanism, comprising a shank, a gripper jaw suitably attached to said shank, a second jaw, a pivotal connection between the two jaws, a second shank, a hinge joint connecting said second jaw and its shank, and yielding means arranged to tend to hold the joint fixed whereby the jaws are normally separated.
17. In a grippers mechanism, the combination with a movable gripper member and a coöperating gripper member, of actuating means for said movable gripper member, a swinging link extending laterally from the movable gripper member for causing said member to travel in a curved path when it is actuated, and means coöperating with said swinging link for determining the path in which the movable gripper member is actuated.
18. In a grippers mechanism, the combination with a fixed gripper member and a relatively movable gripper member, of mechanism including a single link connection between the members for actuating and guiding said movable member toward gripping position in a nearly straight path outwardly and downwardly over the stock to be gripped and then in a curved path laterally toward the coöperating member for gripping the stock.
19. In a grippers mechanism, the combination with a movable gripper member and a coöperating gripper member, of a swinging link to which said movable gripper member is connected, means for actuating said movable gripper member, and controlling means coöperating with said swinging link for causing said member to travel in approximately the direction of its length for embracing the stock and thereafter to turn toward the coöperating gripper member for gripping the stock.
20. In a grippers mechanism, the combination with a movable gripper member and a coöperating gripper member, of a rod, a link pivotally connected to the rod and to the movable gripper member, said rod being arranged to be actuated lengthwise for moving the link and movable gripper member longitudinally, and means for effecting and controlling flexure of the joint between the movable gripper member and link whereby the movable gripper member is turned as well as moved longitudinally by force transmitted from the rod through the link.
21. In a grippers mechanism, the combination with a movable gripper member and a coöperating gripper member, of actuating and guiding mechanism for advancing said movable gripper member in the direction of its length to embrace the stock without substantial movement inwardly toward the other member and for thereafter rocking said gripper member toward the coöperating member to grip the stock.
22. In a machine for working an upper over a last, a grippers mechanism comprising a rocking jaw and a coöperating jaw, said rocking jaw having an arm extended laterally toward and pivotally connected to the coöperating jaw, combined with means for actuating said rocking jaw about said pivotal connection to grip and release stock, said means including a push bar and also a cam and a yielding device to hold the rocking jaw in engagement with the cam.
23. In a machine for working an upper over a last, a grippers mechanism comprising a rocking jaw, an actuator, and a coöperating jaw, said rocking jaw having an arm extended laterally toward and pivotally connected to the coöperating jaw and an arm extending at an angle to the lateral arm and pivotally connected to the actuator, said parts being constructed and arranged to permit the actuator to form an acute angle with the first-mentioned arm when the jaws are in clamping relation and additional means for guiding the rocking jaw from and toward the other jaw.

24. In a machine for working an upper over a last, a grippers mechanism comprising a rocking jaw, and a coöperating jaw, said rocking jaw having an arm extended laterally toward and pivotally connected to the coöperating jaw, an arm extending at an angle to the lateral arm, a carrier on which the two jaws are mounted, a rod guided by the carrier for right-line movement therein to actuate the rocking jaw, and a link connecting the rod and the second arm to transmit movement from the rod to the rocking jaw.
25. A lasting machine gripper, having in combination, a movable jaw, a coöperating jaw, an arm extending laterally from one of said jaws toward the other jaw and pivotally connected therewith, means flexibly connected to the movable jaw to effect a relative closing and opening movement of the jaws and additional means for controlling the direction of the movement of said movable jaw toward and from the coöperating jaw.
26. A grippers mechanism comprising co-operating jaws one of which is movable and connected by a link to the other, means for closing the jaws in two steps in the first of which the jaws are moved lengthwise to embrace the stock and are caused to approach approximately and in the second of which steps the movable jaw is rocked sharply toward the fixed jaw without substantial longitudinal movement.
27. A grippers mechanism comprising co-operating jaws one of which is movable and connected by a link to the other, means for effecting an actuation, including a relative lengthwise movement, of the jaws to embrace the stock and an approximate closing upon the stock, and additional means for effecting a final closing and secure holding of the jaws.
28. A grippers mechanism comprising co-operating jaws one of which is movable and connected by a link to the other, means for closing the jaws including the push rod 15, the link 17, and the cam 20 having a low portion which is operative during the movement of the jaws to embrace the stock and approximately close thereon, and a portion for sharply rocking the movable jaw toward the other jaw to effect final closing and locking of the jaws.
29. A grippers mechanism comprising co-operating jaws, one of which is connected to the other for lengthwise and rocking movements, and having the push rod 15, the link 17 connecting said rod to the movable jaw, and the cam 21 having a surface at its lower portion arranged to rock the movable jaw to force its lower end toward the co-operating jaw during the final closing of the jaws.
30. A grippers mechanism comprising co-operating jaws one of which is connected to the other for lengthwise and rocking movement, means including a push rod to actuate the movable jaw endwise and rock it for effecting approximate closing of the jaws, and additional means constructed and arranged to become operative during the last part of the movement of the push rod to rock the movable jaw for effecting final closing of the jaws.
31. In a grippers mechanism, the combination with a pivoted jaw, of a coöperating jaw, a link pivotally connected to both jaws, means for initially rocking the pivoted jaw to grip the stock, and additional means for finally closing the jaws.
32. In a grippers mechanism, the combination with a pivoted jaw, of a coöperating jaw, means for initially rocking the pivoted jaw about a point laterally removed a substantial distance from the pivoted jaw toward the coöperating jaw to grip the stock, and additional means arranged to become operative only after the initial rocking movement for forcing the pivoted jaw toward the fixed jaw to effect final closing and holding of the jaws.
33. A grippers mechanism having, in combination, two jaws having a swinging link connection between them, and mechanism for actuating the jaws in two steps to grip the stock, including means to rock one of the jaws toward the other for initially closing the jaws upon the stock and additional means becoming operative subsequently to effect final closing of the jaws.
34. A grippers mechanism having, in combination, two jaws having a swinging link connection between them, and mechanism for actuating the jaws in two steps to grip the stock, comprising means for rocking one of said jaws for initially gripping the stock and additional means including a surface inclined to the direction of relative movement for effecting final closing of the jaws.
35. In a grippers mechanism the combination with the two jaws 14 and 16, the connection 18 between them to permit relative movement, the wedge cam 20 for effecting final closing of said jaws, and the rod 15 coöperating with the connection 18 to effect relative closing movement of the jaws independently of the wedge.
36. In a grippers mechanism the combination with two jaws, a link pivotally connected to both of said jaws whereby they are relatively movable longitudinally, a wedge cam having an acting face oblique to the direction of such movement and arranged to effect a closing of the jaws upon stock between them, and an operating rod connected to said jaws independently of the wedge.
37. In a grippers mechanism the combination of the two jaws 14, 16, the rod 15, and

- links 17 and 18 arranged to move jaw 16 lengthwise relatively to jaw 14 in closing and opening the grippers and the cam surface 20 arranged to be engaged by the heel 5 21 of the jaw 16 after the initial closing movement for giving to jaw 16 a more powerful final gripping movement for seizing and holding the stock between the two jaws.
38. In a grippers mechanism the combination with two jaws, means for moving one jaw lengthwise relative to the other in closing and opening said jaws, and additional means arranged to become operative
- only after the initial closing movement for forcing the jaws together more powerfully 15 to effect final gripping and holding of the stock.
- In testimony whereof we have signed our names to this specification in the presence of two subscribing witnesses.

Corrections in Letters Patent No. 1,005,234.

It is hereby certified that in Letters Patent No. 1,005,234, granted October 10, 1911, upon the application of Sherman William Ladd, of Boston, and Edward Allin Stiggins, of Beverly, Massachusetts, for an improvement in "Grippers for Lasting-Machines," errors appear in the printed specification requiring correction as follows: Page 4, line 21, for the word "latter" read *later*; same page, line 47, for the word "fixed" read *flexed*; and that the said Letters Patent should be read with these corrections therein that the same may conform to the record of the case in the Patent Office.

Signed and sealed this 28th day of November, A. D., 1911.

[SEAL.]

E. B. MOORE,
Commissioner of Patents.
